UNITED STATES PATENT OFFICE.

WILEY EDMONSON, OF BICKNELL, INDIANA.

DIE.

988,866.

Specification of Letters Patent.

Patented Apr. 4, 1911.

Application filed June 14, 1910. Serial No. 566,807.

To all whom it may concern:

Be it known that I, WILEY EDMONSON, a citizen of the United States, residing at Bicknell, in the county of Knox and State 5 of Indiana, have invented new and useful Improvements in Dies, of which the following is a specification.

This invention relates to improvements in dies and has for its object the provision of a 10 die to be employed for forming and sharpening bits such as are employed with power-actuated drills in the mining of coal and the like.

With the above and other objects in view, 15 which will more fully hereinafter appear, the present invention consists in certain novel details of construction and arrangement of parts, hereinafter fully described, illustrated in the accompanying drawings, 20 and more particularly pointed out in the appended claim; it being understood that various changes in the form, proportion, size, and minor details of the device may be made, within the scope of the appended claim, 25 without departing from the spirit or sacrificing any of the advantages of the invention.

In the accompanying drawings, forming 30 part of the specification;—Figure 1 is a detail perspective of the lower die member. Fig. 2 is a similar view of the upper die member. Fig. 3 is a sectional end view taken through the members when the latter bear one upon the other and showing a bit being operated upon.

Similar numerals of reference are employed to designate corresponding parts throughout.

The device is intended for use with drop 40 presses, trip hammers and the like and when the bits are properly heated and properly positioned on the lower member, the upper member which is vertically movable and preferably carried by the plunger of the 45 press or hammer is moved into engagement with the bit and press to shape, trim and sharpen the bit.

The lower member is designated in general by the numeral 5 and comprises an ob- 50 long metallic block the lower portion of which is, on its opposite sides provided with inclined grooves to be formed in a dove-tailed tongue 6 to be received by a dove-tailed slot on the bed of a press (not shown).

55 The upper face of the lower member 5 pre-sents, in side elevation a stepped surface, the

lowest portion of which is designated by the numeral 8 and is perfectly plane and horizontal, with respect to the longitudinal center of the block and extends from one end 60 thereof to a point adjacent the middle of the block. That portion of the upper face of the block at the inner end of the horizontal surface 8 is, at a point intermediate the inner end of the surface 8 and adjacent end 65 of the block beveled, as shown at 9, this beveled surface extending upwardly from one side of the block to a point adjacent to the longitudinal center of the block, the portion beyond the inner end of the beveled surface 70 9 being designated by the numeral 10 and lying in a plane with the surface 8. The end portion of the block at the inner side of the beveled surface 9 rises to a point above the plane of the highest point of the beveled surface 75 9. Extending through an opening in the end portion 11 of the block is what will subsequently be termed an anvil 12. This member is substantially square in cross section and when so positioned as shown in the 80 drawings its upper face will form a continuation of the beveled surface 9, and one of its sides 12' incline upwardly at obtuse angles to the surface 10 of the block, it being understood that the opening through which 85 the anvil extends is located a trifle beyond the inner end of the beveled surface 9.

The upper die member is designated in general by the numeral 13 and corresponds in contour to the lower die member 5. Like 90 the lower die member 5 the upper die member has its upper portion provided with a dove-tailed tongue 14 to be received by a dove-tailed groove in the plunger of the press (not shown). The lower or striking 95 surface of the upper member 13 presents, in side elevation a stepped surface, one end portion of which is designated by the numeral 15. The opposite end surface of the lower face of the block is designated by the 100 numeral 17, this end surface being plane and corresponding in area to the area of the end portion 8 of the lower block. Formed between the end portions 15 and 17 is a beveled surface 16 corresponding in length 105 and width approximately to the beveled surface 9 and overlying the said beveled surface 9 so that when the surface 15 bears on the surface 11 a wedge-shaped opening will be presented between the beveled surfaces 110 9 and 16. The beveled surface 16 terminates in a depending extension 18, the inner side

of which is beveled as shown at 19 to bear on the side 12' of the anvil, the lower face of the extension 18 being adapted to bear on the surface 10 of the lower block.

5 With this construction it will be manifest when the surfaces just described bear one upon the other and the V-shaped opening presented as before described that the portion of the upper member extending beyond 10 the inner end of the beveled surface 16 will bear on one side of the anvil 12, and it will be manifest when the lower member descends to this position one edge of the anvil 10 will coöperate with an edge of that portion of the surface beyond the inner end of the beveled surface 16 to form a shear so that an object extending beyond the said edge of the anvil will be trimmed.

20 From the foregoing, it is evident that I have provided a device which is comparatively simple in structure and inexpensive in manufacture, embodying few parts and these so arranged that the danger of derangement will be reduced to a minimum.

25 I claim:—

A die comprising a lower member having on its upper face and between its opposite ends a beveled portion extending down-

wardly from a point adjacent to the longitudinal central line of one side of the member, and further provided with a recess extending laterally from the inner side of the beveled surface and opening through one side of the member, an anvil of rectangular cross section extending through said opening of the lower member and having one of its sides forming a continuation of the said beveled surface, and another side inclining upwardly from the floor of the recess, an upper member having a portion of 40 its lower face beveled similar to the beveled portion of the lower member and positioned to overlie the said beveled portion of the lower member, the said lower face of the upper member being further provided at 45 the inner end of the beveled surface thereof with a depending extension, one side of which is adapted to bear on one side of the anvil and the face of which bears on the floor of said recess.

50 In testimony whereof I affix my signature in presence of two witnesses.

WILEY EDMONSON.
